GLOVE HOLDING ATTACHMENT FOR HANDBAGS OR THE LIKE

Paul Weinberg, Los Angeles, Calif.

Application February 10, 1950, Serial No. 7,873

Term of patent 14 years

(Cl. D87—2)

To all whom it may concern:

Be it known that I, Paul Weinberg, a citizen of the United States, residing at Los Angeles, in the county of Los Angeles and State of California, have invented a new, original, and ornamental Design for a Glove Holding Attachment for Handbags or the like, of which the following is a specification, reference being had to the accompanying drawing, forming part thereof.

In the drawing

Fig. 1 is a front elevational view of a glove holding attachment for handbags or the like, showing my new design;

Fig. 2 is a side elevation thereof.

I claim:

The ornamental design for a glove holding attachment for handbags or the like, as shown.

PAUL WEINBERG.
